BURGLARPROOF COFFER

Charles Stengel, Budapest, Hungary, assignor to
 Istvan Wittinger and Szilard Stankovits, both
 of Budapest, Hungary

Application February 17, 1932, Serial No. 593,599
 In Hungary February 20, 1931

8 Claims. (Cl. 116—70)

The present invention relates to burglarproof coffers or safes which are surrounded by air chambers connected to alarm apparatus through pipe lines so that said alarm apparatus is operated when the pressure in the air chambers changes.

Some of the safes of this kind present numerous disadvantages. For instance their walls can be bored without connecting the air chambers to the atmosphere, and without operating the alarm apparatus which can be done by holding the drill within an airtight enclosure. It is also possible to cut off the alarm apparatus from the safe for instance by pressing or melting together the walls 15 of the connecting pipe, so as to prevent the air from flowing from the safe to the alarm apparatus.

In order to obviate the above disadvantages and to obtain a really burglarproof safe there is 20 provided according to the present invention a safe with two or more layers of air chambers, such layers totally surrounding the safe and the pressures in the interior of these chambers being different. The arrangement is such that if a 25 wall of the safe is pierced without communication of the air chambers with the atmosphere, the contents of the two superposed air chambers are mixed, and in consequence the pressure in the air chambers is altered and the alarm apparatus 30 operated.

Although in this specification I always mention air chambers, these spaces may be also filled with a gas other than air, or broadly speaking with a fluid.

Another feature of the invention consists in 35 constructing the pipe lines, which connect the safe with the alarm apparatus, of two or more pipes communicating with different air chambers of the safe and containing air at different pressures and arranging said pipes so that if an attempt is made to cut off the safe from the alarm apparatus, one of the pipes is perforated, the pressures within the pipes equalized, and the alarm apparatus operated.

The invention also relates to locking means 45 adapted to cooperate with the air chambers of the safe and to operate the alarm apparatus if a person who does not possess all the necessary keys or is not perfectly familiar with the lock attempts to open the same.

In the drawing one form of the invention is shown by way of example.

Fig. 1 is a vertical section of a part of the coffer or safe.

Fig. 2 is a partial horizontal section.

Fig. 3 is a fragmentary view, partly broken away and part in section, of the door of the safe and locking devices associated therewith.

Fig. 4 is a diagrammatical view of an alarm apparatus associated with the safe.

In Figs. 1 and 2 the usual fire-proof layers are not shown but may be applied if desired.

In the form shown in Figs. 1 and 2 the safe has treble walls which form air chambers 1 and 2 hermetically sealed from the atmosphere. All 10 the air chambers 1 communicate with one another so that the pressure within these chambers is the same. The chambers 2 are also interconnected, and separated from the chambers 1, so that the pressure in the chambers 2 may differ 15 from that in the chambers 1. Preferably in the chambers 1 a pressure below atmospheric and in the chambers 2 a pressure above atmospheric is maintained. The door 3 of the safe also comprises three walls forming air chambers 1 and 2 20 connected to the immovable or stationary air chambers of the safe by flexible pipe lines 4 and 5 as is usual in safes fitted with air chambers. The vertical edge of the door 3 extending between the hinges (not shown) is formed by two 25 cylindrical portions 6 and 7 arranged in one another and forming air chambers 1 and 2 which are connected to the other chambers of the door through pipes or ports 8 and 9 respectively. The flexible pipe 4 connects the annular chamber 1 30 of the cylinder 6 to one of the immovable chambers 1 of the safe and the pipe 5 establishes communication between the interior of the cylinder 7 and one of the fixed chambers 2. The pipes 4 and 5 are long enough to secure free turning 35 of the door and are situated in a vertical, longitudinal space 41, so as to be accessible only after removing the door 3.

The safe is totally surrounded by the layer of the air chambers 1 as well as by the layer of the 40 chambers 2 so that at no point can the safe be pierced without passing the drill through two air chambers containing air at different pressures.

The air is sucked out from or admitted into the air chambers 1 and 2 for instance through 45 pipes 10 leading into the interior thereof. When the desired pressure in the air chambers is established the pipes 10 are hermetically sealed and are not accessible without opening the door 3.

Although various types of alarm apparatus 50 indicating the changes of pressure in the interior of a container are known, I desire to utilize a preferred form of this apparatus shown in Fig. 4. The apparatus, which may be installed in the room of the guard or at the police station, com- 55

prises a fixed plate 11 having a bore 21, the latter being connected through a pipe line which will be described hereinafter, to the air chambers 1 of the safe; within the chambers 1 there is a 5 partial vacuum, so that a plate 12 preferably made of rubber and disposed at the underside of plate 11 is pressed to the latter by the atmospheric pressure. To the plate 12 is secured a rod 13 provided with an aperture 14 and holding a 10 weight 15.

A rod 16 passes through the aperture 14 and forms part of an alarm bell 17 adapted to ring under the action of a spring when the rod 16 is depressed. The construction of this bell may 15 be quite similar to that of the alarm-clocks, which are also operated when a certain part thereof is moved from its normal position.

If the air chambers 1 are connected to the atmosphere or to the chambers 2 containing air 20 at a pressure above atmospheric, the pressures are equalized and the plate 12 falls down moving the rod 16 out of its normal position and sounding the bell.

The pipe line or lines connecting this or other 25 alarm apparatus of any known construction to the air chambers of the safe must be, as already mentioned, of such a construction as to prevent the apparatus from being cut off from the safe. With this object in view the connecting line is 30 made of at least two pipes, the pipe 18 of which communicates with the air chambers 1 and contains air at a pressure below atmospheric, while the other pipe numbered 19 and disposed within pipe 18, communicates with the chambers 2 and 35 contains air at a pressure above atmospheric. By this arrangement any attempt to destroy the pipes 18, 19 causes a mixing of the air contents which are at different pressures and thus the 40 operation of the alarm apparatus, in the same way as in the case of chambers 1 and 2. According to Fig. 1 the pipe lines are attached to the top of the safe, but it is to be understood that said lines may also be arranged under the floor, in which case they communicate with air chambers situated at the bottom of the safe.

In order to guard against the connecting lines being melted or compressed to form a solid body, the pipe 19 may be made of a material of low melting point, for instance lead and another 50 pipe, numbered 20, may be arranged within pipe 18, said pipe 20 being also connected to the chambers 2 and being made of a rigid and fragile material, for instance glass. By this means both the heating and compression of the pipe line 55 cause destruction of one of the interior pipes and thus mixing of the air charges.

If an apparatus according to Fig. 4 is employed, the bore 21 of the plate 11 is connected to the pipe 18, while the pipe 19 may project out 60 of pipe 18. The pipe 20 is connected to pipe 19 within or outside the larger pipe 18. The pipe 19 may lead to an alarm apparatus which indicates the reduction of pressure in any well known manner.

65 The alarm apparatus is also operated if the pipe lines or the walls of the safe are melted in case of a fire.

It will be understood that the number of and 70 the pressure in the air chambers of the safe may be varied within wide limits, the essential feature being the provision of at least two air chambers extending over the whole area of the safe, these chambers containing air at different pressures.

The door 3 may be fitted with a locking device 75 of any known construction. Preferably this de-

vice is disposed in a cover 23 (Fig. 2) and operates bolts as at 22 which penetrate into sockets as at 24 secured to the wall of the safe and arranged in the interior of an air chamber.

In order to cause a change of pressure in the 5 air chambers and subsequent operation of the alarm apparatus when an attempt is made by a person who is not quite familiar with the lock 10 to open the safe, the device shown in Fig. 3 may be employed. It may be mounted on the rear 15 wall c or in any preferred manner as by ledges l carried by said wall. It may be stated that one of the bolts 22 is operated by a lock 29, the other bolts 22 (not shown in Fig. 3) being connected to the said bolt in any known manner. Between the 20 keyhole 24 of the lock 29 and the inner wall of the door 3 a small vessel 25 is provided which is very fragile and may be a thin walled closed glass container connected by a flexible pipe 26 to one of the air chambers of the door 3. The 25 container 25 is mounted in a frame 27 pivoted on a bolt 28 fixed in the door 3. Beside the lock 29 there is another lock 30 including the lock-bolt 31 which is pivotally connected to the frame 27 by means of a connecting rod 32. Behind the 30 keyhole not shown of the lock 30 there is a vessel 34 communicating with an air chamber of the door and being able to swing to the right in the same manner as the vessel 25. Finally, a lock 35 arranged beside the lock 30 is adapted to swing 35 the vessel 34 by a shifting movement of the lock-bolt 36, in the same manner as the lock-bolt 31 turns the vessel 25.

In operation, when the door 3 is closed, the 40 parts are in a position shown in Fig. 3 in full lines. The vessels 25 and 34 normally are in the paths of the keys inserted into the keyholes and if it is attempted to force a key into these keyholes, the vessels are broken and the air chambers become connected to the atmosphere causing 45 a change of pressure in said chambers and an operation of the alarm apparatus. The opening of the door is effected by inserting firstly the key 35a of the lock 35 into its keyhole and turning it, said key engaging a kerf 36b in the bolt 45 36 and causing said bolt to shift to the right thereby swinging the vessel 34 into the position shown by dotted lines. Now it is possible to insert the key into the keyhole of lock 30 and to shift the lock-bolt 31 by turning this second key, 50 it being understood that the lock bolt 31 is identical with lock-bolt 36 and similarly operated. This causes the swinging of the vessel 25 into the position shown in dotted lines, so that the third key can be inserted into and turned in the key-hole 24 causing the withdrawal of the lock-bolt 22 shown in Fig. 3. As already mentioned, all the 55 lock-bolts 22 are interconnected in a known manner, so that they are withdrawn simultaneously whereupon the door will be unlocked. For closing the door the lock 29 is operated and thereafter the lock 30 is operated causing the vessel 25 to swing to its normal position behind the keyhole 24; finally the lock 35 is operated for swinging the vessel 34.

In order to make it almost impossible for a 60 person who is not familiar with the locking device even if such person possesses the necessary keys to open the door 3 without operating the alarm, I provide the locking device with a fragile 65 vessel communicating with the air chambers and being normally in a position, in which a certain part of the locking device breaks it during the opening procedure, unless this vessel is moved away in a suitable moment.

For this purpose a vessel 37 connected to an air chamber by a flexible pipe 38 is pivotally mounted in the locking device. If the door 3 is closed, this vessel 37 is in a position shown in full lines, so that the pointed end of an arm 40 secured to the frame 21 breaks it, when the lock-bolt 31 moves from the left to the right. In order to prevent a destruction of the vessel 37 the pivot 39 rigidly secured to the frame of this vessel, extends to the front surface of the door 3 and ends in a handle 39a. By turning to the right the pivot 39 the vessel 37 will be swung into the position shown in dotted lines, so that the arm 40 will move quite freely. It will be understood that the vessel 37 is swung to the right into its dotted line position by the handle 39a before the lock 30 is operated. Thus the opening procedure consists of the following operations: Turning the key of the lock 35, turning the pivot 39 to the right, turning the key of the lock 30, and turning the key of the lock 29. Should the pivot 39 be turned to the left, the vessel 37 is pressed against the arm 40 and breaks.

I claim:

1. A burglar proof coffer or safe having two non-communicating fluid-containing chambers extending over the whole area thereof, means adapted to cooperate with a pumping mechanism for placing the fluid contents of each chamber under a pressure different from the pressure in the other chamber, alarm apparatus adapted to operate when the pressure in said chambers is altered, a piping system connecting said coffer with said alarm apparatus, said system comprising a conduit connecting one of said chambers with said apparatus, and piping extending through said conduit and connecting the other chamber with said apparatus.

2. A burglar proof coffer or safe as claimed in claim 1, in which said piping comprises two small tubes one of said tubes being formed of fragile material and the other one of a material of a low melting point.

3. A burglar proof coffer or safe having treble walls forming two layers of hermetically sealed gas chambers, the chambers of one layer communicating with one another and totally surrounding the coffer, means adapted to cooperate with a pumping mechanism for placing the gas contents of each chamber of one layer under a pressure different from the pressure in the chambers of the other layer, alarm apparatus adapted to operate when the pressure in said chambers is altered, and individual pipes connecting

said chambers with said alarm apparatus respectively, one of said pipes being arranged within the other.

4. A burglar proof coffer or safe as claimed in claim 3 in which one of said pipes is formed of a material having a low melting point.

5. A burglar proof coffer or safe as claimed in claim 1 comprising a lock having a keyhole therein, a fragile vessel adapted to be moved in register with said keyhole and to be removed from such position, a flexible tube connecting said vessel to one of the chambers of the coffer, and another lock including a part positionable to accomplish said movements of this vessel.

6. A burglar proof coffer or safe as claimed in claim 1 comprising a lock having a keyhole therein, a fragile vessel adapted to be moved in register with said keyhole and to be removed from such position, a flexible tube connecting said vessel to one of the chambers of the coffer, another lock having a keyhole and a part positionable to accomplish said movements of this vessel, a further fragile vessel adapted to move in register with the keyhole of said second lock and to be removed from such position, a flexible tube connecting said further vessel to one of the chambers of the coffer, and a third lock having a part positionable to accomplish said movements of the last mentioned vessel.

7. A burglar proof coffer or safe as claimed in claim 1 comprising a lock having a keyhole therein, a fragile vessel adapted to be moved in register with said keyhole and to be removed from such position, a flexible tube connecting said vessel to one of the chambers of the coffer, another lock having a part positionable to accomplish said movements of this vessel, a second fragile vessel connected to one of the chambers of the coffer, an arm adapted to press against said second vessel during the unlocking of the coffer, and means for removing said second vessel from the path of said arm.

8. In a burglar proof coffer or safe at least two non-communicating chambers on the whole area thereof, one of said chambers being charged with fluid at a pressure below atmospheric and another of said chambers with fluid at a higher pressure, an alarm apparatus comprising a fixed plate having a bore connected to that one of said chambers containing fluid at a pressure below atmospheric, a second plate held by suction to the first one, a bell, and means operated by the falling of said second plate for ringing said bell.

CHARLES STENGEL.
